The Richmond Fireproof Door Company, Richmond, Ind., a corporation of Indiana

Application February 10, 1936, Serial No. 63,153

8 Claims. (Cl. 187—52)

This invention relates to an operating mechanism which is applicable to sliding doors, such as for instance, doors located on elevator cars and at floor landing openings to elevator hatches.

5 An object of the invention is the provision of an operating mechanism which will operate two units of doors simultaneously.

Another object of the invention is to provide a clutch mechanism which, when operated in 10 connection with an operating mechanism, will operate a second unit of doors and thereby eliminate the necessity of providing a separate operating unit for each unit of doors to be operated.

Still another object of the invention is the provision of a dual operator which is efficient in its 15 operation, which is simple of construction and operation, and which is economical to manufacture and to maintain in operative condition.

Other objects and advantages of the invention 20 will suggest themselves in the course of the following description, and that which is new will be correlated in the appended claims.

The most satisfactory manner of carrying out the principles of the invention in a practical, economical, and efficient manner is shown in the accompanying six sheets of drawings, in which—

Figure 1 is an exterior or shaft side elevation of an elevator car having horizontally sliding doors suspended thereon, with the operating mechanism 30 for the doors being secured on the top of the elevator car, and with the operating arms extending from the operating mechanism to the doors, and with the doors being shown in closed position.

35 Figure 2 is an enlarged detail showing the break joint formed between the arm members 14 and 16.

Figure 3 is a shaft side elevation of a pair of horizontally sliding floor landing doors, the same being equipped with operating arms and with an 40 engaging fin attached to the operating arms, and with the doors being shown in closed position.

Figure 4 is an enlarged detail showing the break joint formed between the arm members 40 and 44.

45 Figure 5 is an elevation of the operating mechanism shown with the clutch mechanism in normally disengaged position.

Figure 6 is an elevation of the operating mechanism in the position which is assumed when the 50 doors are in open position, and with the clutch in normally engaged position.

Figure 7 is a top plan view of the clutch mechanism with the same being in normally disengaged position.

Fig. 8 is a side elevation of the clutch mechanism, taken from line 8—8 of Figure 7.

Figure 9 is a rear side elevation of the clutch mechanism, taken from line 9—9 of Figure 8.

Figure 10 is a top plan view of the clutch mechanism in normally engaged position.

Figure 11 is a side elevation of the clutch mechanism, taken from line 11—11 of Figure 10.

Figure 12 is a front elevation of the clutch mechanism, taken from line 12—12 of Figure 10.

Figure 13 is a detail cross section through the air check cylinder, taken on line 13—13 of Figure 11.

Figure 14 is a detail longitudinal vertical section through the clutch mechanism with the 15 same being shown in engaged position, taken on line 14—14 of Figure 12.

Figure 15 is a top plan view of the yoke and bracket members and the engaging rollers, taken 20 from line 15—15 of Figure 11.

Figure 16 is a detail longitudinal section through one of the yoke arms, taken on line 16—16 of Figure 15.

Figure 17 is a detail vertical section through one of the bracket members and a roller, taken 25 on line 17—17 of Figure 15.

Figure 18 is a detail longitudinal vertical section through the clutch mechanism with the same being shown in disengaged position, taken on line 18—18 of Figure 9.

Figure 19 is a detail section through one of the air check valves, taken on line 19—19 of Figure 7.

Figure 20 is a detail isometric view of the clutch-carrying bar and the associated members thereof.

Similar characters designate like parts throughout the several views.

In order that the construction, the operation, and the advantages of the invention may be more fully understood and appreciated, I will now take 40 up a detailed description thereof, in which the same will be more fully and comprehensively set forth.

In the drawings, A designates the elevator car on which the doors B and B' are slidably suspended by means of the rollers C mounted on the track D. I designates the operating unit which is rigidly secured on the top of the elevator car by means of the bolts 2. 3 designates the crank arm which is secured to the projecting end portion of the operator shaft I'. 4 designates a mounting angle which is rigidly secured to the top of the elevator car, the same having the upwardly extending end bracket 4' and the brace member 4'' rigidly secured thereto. The operating 50

55

arm 5 is pivotally secured to the mounting angle 4 by means of the bolt 6, and the lower portion of the operating arm 5 is slidably secured to one edge of the door B by means of the bolt 7 extending through the slotted bracket 8, with the bracket 8 being rigidly secured on the edge of the door B by means of the cap screws 8'. The arm 9 extends horizontally from the arm 5, and is pivotally secured thereto by means of a cap screw 10 which is located midway between the bolts 6 and 7. The opposite end of the arm 9 is pivotally secured to the angle bracket 11 by means of the cap screw 12, the angle bracket 11 is rigidly secured on the edge of the door B' by means of the cap screws 11'.

The angular-shaped lever 13 is pivotally secured through the arm 5 and the mounting angle 4 by means of the bolt 6. The arm 14 is pivotally secured to the lower end of the lever 13 by means of the cap screw 15, and is pivotally secured, at its lower portion, by the cap screw 17 to the bar 16 which is slidably secured to the edge portion of the door B by means of the bolt 7, with the bar 16 then extending across the door and providing a handle for manual operation of the doors. A break joint is formed between the bars 14 and 15 as more clearly shown in Figure 2. The bar 16 has the projecting pin 18 rigidly secured thereto, the same registers with the notch 14' which is formed in one edge of the bar 14. The cap screw 19 is threaded into the bar 14 with the end of the cap screw being convex and registering with the concave aperture 16' which is formed in the surface of the bar 16. By the above-described arrangement, when the power supply is broken from the doors, the doors may be manually operated without removing any of the operating arms or the connections thereof.

The connecting arm 20 extends from the crank arm 3 to the upper end of the lever 13, the same being pivotally secured to the crank arm by means of the cap screw 3' and is pivotally secured to the upper end of the lever 13 by means of the cap screw 21. The connecting arm is comprised of two separate pieces of bar which are adjustably secured together by means of the cap screw or bolt 22, which allows the arm 20 to be adjusted for any variations which might occur in the other members of the operating arms. An air check assembly 23 is pivotally secured, at one end, to the upwardly extending bracket 4', and is pivotally secured, at the opposite end thereof, to the connecting arm 20 by means of the bolt 24, and provides a cushioning means for the operating arms during the operation thereof.

The bar 25 is pivotally secured to the upper end of the operating arm 5 by means of the bolt 26 and extends horizontally therefrom, as shown in Figures 1, 5, and 6. The arm 27 is pivotally secured to the mounting angle 4 by means of the bolt 28 and extends upwardly therefrom, and is pivotally secured, at its upper end, to the bar 25 by means of the cap screw 29. It will be noted that the arm 27 is parallel with relation to the operating arm 5, and that the distance between the cap screw 6 and the bolt 26 is the same as the distance between the bolt 28 and the cap screw 29, thereby maintaining the arm 27 and the operating arm 5 in parallel relation with each other at all times.

Referring now to Figure 3, E and E' designate the horizontally slid able floor landing doors which are suspended on the rollers F positioned on the tracks G. The tracks G are rigidly secured to the usual hanger plate which is anchored into

the wall above the door opening in the usual manner. 30 designates the bracket members which are rigidly secured, at their lower portions, to the hanger plate in any well-known manner. The arm 31 is pivotally secured, at its upper end, to one of the bracket members 30 by means of the cap screw 32, and is slidably secured, at its lower end, through an elongated aperture formed through the bracket 34 by means of the bolt 33. The bracket 34 is rigidly secured on the edge of the door E by means of the cap screws 34'.

The bar 35 extends horizontally from the arm 31 at a point located midway between the cap screw 32 and the bolt 33, and is pivotally secured to the arm 31 by means of the cap screw 36, and is pivotally secured at the opposite end thereof, to the angle bracket 37 by means of the bolt 38. The angle bracket 37 is rigidly secured on the edge of the door E' by means of the strap 39 and the cap screws 39'. The arm 40 is pivotally secured to a second bracket member 30 by means of the cap screw 41 with the upper end portion thereof being pivotally secured to one end of the horizontally positioned bar 42 by means of the bolt 43. Near the lower end of the arm 40 the same is pivotally secured to the upper end of the bar 44 by means of the cap screw 45. The projecting pin 40' is rigidly secured to the face of the arm 40 and is located between the cap screw 45 and the extreme lower end of the arm 40. A notch 44' is formed in one edge of the bar 44 and is adapted to receive the pin 40'. The break joint formed by the arm 40 and the bar 44, which allows manual operation of the doors E and E', is clearly illustrated in broken position in Figure 4. The bar 44 is pivotally secured to the arm 31 by means of the cap screw 46, and a handle member 47 is rigidly secured to the lower end portion of the bar 44 by means of the rivets 47'. The bar member 48 is pivotally secured, at its lower end, to a third bracket member 30 by means of the cap screw 49, and with the upper end thereof being pivotally secured to the central portion of the fin member 50. The fin member 50 is positioned vertically and has the central portion 50' which is rigidly secured through the end portion of the bar member 42 by means of the bolts 51. 52 designates an electrical contact switch which is connected in series with the elevator control circuit. The electrical contact switch 52 has a contact pin extending outwardly therefrom, with the contact pin being in contactable relation with the end portion of the base 51. The electrical contact switch 52 is rigidly secured to the structural angle member 53 by means of the bolts 52'.

Referring now to the clutch mechanism and the associated parts thereof in detail, the plate 25' is rigidly secured to the upper surface of the bar 25. The member 54 is rigidly secured to the face of the plate 25' and extends upwardly therefrom. The upward extension 54 has the horizontal portion 55 formed at right angles thereto and is formed integral therewith, the same having the apertures 55' formed therethrough near the end thereof and through which the cap screws 56 extend. The cap screws 56 are threaded into the upper portion of the forward end cap member 57 of the air check assembly. 58 refers to the rear end cap member of the air check assembly. The cylinder is positioned between the end cap members 57 and 58 with the gaskets 60 and 61 placed at the ends of the cylinder. The forward end cap member 57 has a centrally located aperture formed therethrough for the reception of the piston rod 62. The inner or rear end of the 75

piston rod 62 has the turned portion 62' and the threaded portion 62'' formed thereon with the flat washers 63 and the cup washers 64 being secured on the turned portion 62' by means of the nut 65 which is threaded onto the threaded portion 62''. The forward end portion of the piston rod has an aperture formed therethrough for the reception of the connecting pin 88. The end cap members 57 and 58 are rigidly secured on the ends 10 of the cylinder by means of the bolts 66 extending through apertures 57' and 58' respectively, and are rigidly secured by means of the nuts 67. The block member 68 is rigidly secured to the face of the plate 25' and projects forwardly therefrom. 15 The block member 68 has the two apertures 68' formed vertically therethrough which provide for the reception of the pivot pins 69 and 70. The roller brackets 71 and 72 each have upper and lower arms formed thereon and through which apertures are formed vertically. The roller brackets 20 71 and 72 are pivotally secured to the block member 68 by means of the pivot pins 69 and 70 respectively extending vertically therethrough. The pivot pins 69 and 70 are prevented from moving vertically by the cotters 69' and 70' respectively which extend through apertures formed through the pivot pins near each end thereof. The roller brackets 71 and 72 have the rearwardly extending arms 73 and 74 respectively 25 formed integral therewith, and with the same forming the U-shaped channels 75 and 76 respectively. The shafts 77 and 78 are formed integral with the lower portions of the roller brackets 71 and 72 respectively. The rollers 79, together with their bearings 80, are revolvably secured on the shafts 77 and 78 by means of the washers 81 and the pins 82. 30 The yoke shaft 83 has the threaded portion 84 formed on the forward end portion thereof and forming the shoulder 85. The threaded portion 84 is threaded into a threaded aperture 54' which is formed horizontally through the members 25' and 54 with the shoulder 85 being tightened against the rear side of the member 25'. 35 The yoke member 86 has an aperture formed longitudinally through the central portion thereof, and through which the yoke shaft 83 extends. The upwardly projecting arm 87 is formed integrally with the body portion of the yoke member 86, and has a channeled slot 87' formed in the upper end portion thereof with apertures formed horizontally through the upwardly projecting sides of the channeled slot. The pin 88 pivotally secures the upper end of the arm 87 to the forward end portion of the piston rod 62, as shown in 40 Figures 14 and 18. Extending outwardly from the forward end portion of the body of the yoke member are the arms 89 and 90 having the forwardly projecting forks 91 and 92 respectively formed integrally therewith. The forks 91 and 92 each have apertures formed vertically therethrough near the forward ends thereof for the reception of the respective bearing pins 93. A roller 94 is positioned on each of the bearing pins 93 and is located between the upper and the lower portions of each of the forks 91 and 92, and a cotter 93' is secured through the lower end portion of each of the pins 93. The rollers 94 are thereby positioned in the U-shaped channels which are formed in the roller brackets 71 and 72 by the rearwardly extending arms 73 and 74 respectively. The external threads 95 are formed integrally with the rear portion of the body of the yoke member 86. 45 The sheave 96 has the hub portion 97 formed integrally therewith, and into which the internally threaded collar member 98 is rigidly secured by means of the set screw 99. The unit comprised of the sheave 96, the hub 97, and the set screw 99 is threaded onto the threaded portion 93 of the yoke member 86. The sheave 96 is provided with the bearing 100 secured in place by means of the retaining plate 101 and the threaded screws 102. The bearing 100 is secured on the portion 83' of the yoke shaft 83 by means of the bushing 103 and the nut 104 which is threaded onto the threaded portion 83'' of the shaft 83, with the nut 104 being rigidly secured on the threaded portion 83'' by means of the pin 105 which extends through both the nut 104 and the threaded portion 83'', as shown in Figures 14 and 18. The sheave 96 has the groove 96' formed in the periphery thereof for the reception of the belt 106. 50 The electric motor 107 is rigidly supported by the base member 108, the same being secured to the top of the elevator car A by means of the cap screws 109. The motor 107 has an extended shaft on which the sheave 110 is rigidly secured, and the sheave 110 has a groove formed in the periphery thereof for the reception of the belt 106. 55 The arm 90 of the yoke member has the contact arm 111 rigidly secured to the rear side thereof by means of the cap screws 112. The electrical contact switch 113 is rigidly secured onto the upper surface of the angle mounting bracket 114, and the angle mounting bracket 114 is rigidly secured on the forward face of the bar member 25 by means of the threaded screws 115. The contact switch 113 has the projecting contact pin 113' which extends rearwardly therefrom, the same making contact, within the case 113, and completing an electrical circuit through the wires K and K' when the contact pin 113' 60 is pressed by the contact arm 111. 65 A second contact arm 116 is rigidly secured to the forward face of the bar member 25 by means of the threaded screws 117, and extends downwardly therefrom with the foot portion 116' turned at a right angle with relation to the major portion of the arm 116. The contact pin 118 is threaded vertically through the foot portion 116' and is adjustably locked in position by means of the lock nut 119. The electrical contact switch 120 is rigidly secured on the rear side of the mounting angle 4 by means of the threaded screws 121, the same being threaded into the case of the contact switch 120. The contact switch 120 has the contact lever 120' which is hingedly secured at one end thereof, and which makes electrical contact within the case 120 when pressure is applied by the lower end of the contact pin 118, and thereby making an electrical circuit through the wires L and L' when the lever 120' is carried thereon by the bar member 25. 70 The air check valves 122 are connected to their respective end cap members 57 and 58 by means of the threaded conduits 123. The conduits 123 are threaded, at one end thereof, into threaded apertures 57'' and 58'' of the cap members 57 and 58 respectively, and at the opposite ends thereof, into threaded apertures formed in the members 122, as shown in Figure 19. A T-shaped aperture is formed in each of the members 122, 75 as shown in Figure 19, with one terminal of the aperture being formed comparatively smaller than the major portion of the same, and thereby forming a seat against which the ball 127 is forced. A plug 124 is threaded into one termi- 75

nal of the aperture and a threaded aperture is formed vertically through the plug 124 for the reception of the threaded screw 125. A lock nut 126 is tightened against the top portion of the plug to prevent the screw 125 from being accidentally turned. The screw 125 has the slot 125' formed in one side thereof, the same being for the purpose of allowing air to escape from the valve, and permitting a means for controlling the quantity of air drawn into or forced out of the air check cylinder by the piston.

The operation of the mechanism comprising the invention is substantially as follows:

Electricity, for the operation of the electric motor, which is contained within the operator housing 4, and for the clutch motor 107, is obtained from a panel board (not shown) which is located at a convenient position with relation to the elevator hoisting mechanism. A reversing switch (not shown) is mounted on or near the panel board, from which electric wires are extended to the operator motor, and to floor selector push buttons which are located within the elevator car.

Figure 1 illustrates the position of the operating mechanism, the clutch, and the operating arms with the car doors B and B' shown in closed position. Figure 3 illustrates the floor landing doors in closed position with the operating arms therefor being shown in corresponding relation thereto, and with the fin member 50 in position to be engaged by the wheels 79 of the clutch mechanism.

The arrangement, as shown, is designed to be used in connection with what is known as automatic elevators in which floor selector push buttons are located in the elevator cars. When the floor selector button is pushed for any desired floor, the elevator car is controlled by means of automatic electrical devices, and is automatically stopped at the pre-selected floor level. It is to be understood that the mechanism herein shown and described, may be used with equal advantage in connection with any type of electric elevator.

As the elevator car travels to within a predetermined distance of the selected floor (approximately six or eight inches), the clutch motor is automatically energized and rotates the internally threaded collar 98 by means of the drive belt 106 running over the motor sheave 110 and the sheave 96, the latter being rigidly secured to the collar 98 by means of the hub 97 and the set screw 99. When the collar 98 is rotated, the same advances the yoke member 86 by reason of the threaded portion 95 being in mesh with the internal threads of the collar 98. As the yoke member advances from the position as shown in Figure 7 to the position as shown in Figure 10, the same causes the arms 73 and 74, carrying the wheels 79, to be rotated and bringing the wheels 79 into engagement with the fin member 50 of the floor landing door mechanism. When the wheels 79 engage the fin member 50, the electrical circuit to the clutch motor 107 is automatically broken through the contact switch 128 by reason of the contact pin 118 being carried by the contact arm 116 and allowing the electrical contacts within the switch case 120 to separate and thereby breaking the electrical circuit to the motor 107. When the yoke arms have moved forwardly (as shown in Figure 10) the contact arm 111, which is carried by the arm 90, presses against the contact pin 113' of the contact switch 113 with the same forcing the contact points (enclosed within the case 113) together and making

an electrical circuit through the motor 107. The last mentioned circuit to the motor is not operatively completed until it is desired to start the elevator car, and a button has been pushed to start the car, after which the motor 107 rotates in a reverse direction and causes the motor sheave 110, the belt 106, the sheave 96 together with the hub 97 and the collar 98 to be rotated reversely and thereby causes the yoke member 86 with the arms 91 and 92 to be moved rearwardly. As the yoke arms 91 and 92 move rearwardly, the rollers 94 cause the roller brackets 71 and 72 to swing from the position as shown in Figures 10 and 15 to the position as shown in Figure 7, and thereby disengaging the rollers 79 from the fin member 50, after which the elevator car may be moved upwardly or downwardly in the elevator hatch.

An instant after the clutch motor 107 is energized, the motor (contained within the operator 4) is also automatically energized, and rotates the crank arm, through reducing gears, in the direction as indicated by the arrow in Figure 5, to the position as shown in Figure 6. As the crank arm 3 is rotated one-half revolution, the mechanism comprising the operating arms, together with the bar 25 and the clutch mechanism is moved from the position as shown in Figure 5 to the position as shown in Figure 6. As the arm 5 and the lever 13 are pivotally secured to the mounting angle 4, the same open the car doors B and B' as the crank arm 3 rotates. The clutch mechanism, being secured on the bar member 25, is carried thereby, and with the wheels 79 being engaged with the fin member 50 as described above, the fin member 50 is moved thereby, and the floor landing doors are opened by means of the operating arms 42, 48, 31, and 35. As the fin member 50 moves away from the position as shown in Figure 3, the electrical circuit, for the operation of the elevator car hoisting mechanism, is broken through wires extending into the contact switch 52. The electrical contact is broken by reason of the pressure being released from the contact pin by the base portion 50' of the fin member 50.

When it is desired to move the elevator car from a floor landing, a push button is pressed which automatically reverses the current through reversing switches (not shown), to the operator motor and the clutch motor, and the operation of the operating mechanism is consequently reversed, and thereby reversing the movements of the operating arms and the clutch mechanism from that described above, thereby closing the doors on the elevator car and the floor landing doors simultaneously, and also causes the elevator car to move away from the floor landing to another floor which has been selected.

The air check assembly, which is mounted above the yoke member, provides a means for cushioning the travel of the yoke member together with the arms 71 and 72 and the rollers 79 which engage the fin member 50. The upwardly extending arm 87 of the yoke member 86 is pivotally secured to the forwardly projecting end 65 portion of the piston rod 62, and as the yoke member 86 is moved endwise on the shaft 83, the piston is moved correspondingly within the cylinder 59. The air check valves 122 are provided with the balls 127 which are forced downwardly 70 and seal the apertures 122', or are drawn upwardly by the action of the piston within the cylinder. The desired degree of cushioning is obtained by adjusting the threaded screws 125 upwardly or downwardly in their respective 75

threaded apertures in the plugs 124. By turning the adjusting screws 125 outwardly, with relation to the respective plugs 124, a larger opening is obtained, due to the shape of the slots 125', for the escape of air. By turning the adjusting screws 125 inwardly, with relation to the respective plugs 124, a smaller opening is obtained for the escape of air. Thus it is evident that a very fine adjustment for the expelled air can be obtained for cushioning the travel of the yoke member 86, the roller brackets 71 and 72, and the rollers 79, which allows the rollers 79 to quietly but positively engage the fin member 50.

I desire that it be understood that minor changes may be made in the several details, and in the arrangement of the parts herein shown and described, so far as they may fall within the scope of the appended claims.

Having now fully shown and described the invention, what I claim and desire to secure by Letters Patent of the United States, is:

1. In a door operating mechanism, a clutch supported and carried by said operating mechanism and having pivotally positioned roller brackets, a roller rotatably secured to each of said roller brackets, and means for pivotally swinging said roller brackets and rollers toward each other simultaneously and into engaging relation with a fin member of a second door operating mechanism.

2. In combination with a door operating mechanism, a clutch secured to and carried by a bar member of the operating mechanism, said clutch comprising a pair of swingable roller brackets, a roller rotatably secured to each of said roller brackets, means for swinging said roller brackets toward and away from each other simultaneously and bringing said rollers into and out of engagement with a fin member of a second door operating mechanism.

3. A door operating mechanism comprising a plurality of operating arms pivotally secured at the upper portions thereof to stationary members and slidably secured at their lower ends to slideable doors, a single fin member pivotally secured to and carried by one of the operating arms, and a pair of actuated rollers engaging said fin member and transmitting motion through the fin member and the operating arms to the slideable doors.

4. In a door operating clutch mechanism, an internally threaded collar member rotatably positioned on a shaft, a yoke member having one end portion thereof externally threaded with the same being threaded into the internally threaded collar, arms formed at the opposite end of said yoke member, means for rotating said collar member about the shaft and providing longitudinal movement of the yoke member and the arms.

5. In combination with a door operating mechanism, a clutch mechanism having a horizontally positioned slideable yoke member, an arm member formed integrally with said yoke member and projecting upwardly therefrom, a cylinder rigidly mounted above and positioned parallel with relation to said yoke member, a piston slidably positioned within said cylinder with the piston rod thereof extending through one end of

said cylinder with the extending end portion thereof being pivotally secured to the upper end of the upwardly projecting arm member, and means secured adjacent to and interconnected with said cylinder for pneumatically cushioning the travel of the piston at the ends of its travel within the cylinder.

6. A clutch mechanism, comprising in combination, a central shaft rigidly secured at one end thereof and with the opposite end thereof being free, a yoke member slidably positioned on said central shaft, oppositely disposed arms formed integral with one end of said yoke member, external threads formed on the opposite end of said yoke member, a sheave wheel rotatably secured on the free end of said central shaft, an extended hub portion formed integral with one side of said sheave wheel, an internally threaded collar member rigidly secured in said extended hub, with the internal threads of the collar member meshing with the external threads of the yoke member, means for rotating said sheave and collar members and transmitting a longitudinal movement to said yoke member, and means for cushioning the movements of said yoke member at the ends of its longitudinal travel.

7. In combination with a door operating mechanism having a clutch mechanism in connection therewith, a mounting means for said clutch mechanism comprising a bar member having a block rigidly secured thereto, an angular-shaped member extending upwardly from said bar member and said block member with apertures formed through the end portion thereof and providing means for securing an air check assembly thereto, a threaded aperture formed through the vertical leg of the angular-shaped member and providing means for securing a central shaft thereto, and said block member having apertures formed vertically therethrough and providing means for swingably securing roller brackets thereto.

8. A door operating mechanism comprising in combination, a power unit having a rotatable shaft extending therefrom with a crank arm secured thereon, a bar member pivotally secured to the crank arm, a door operating arm pivotally secured through a mounting angle and having the lower end thereof slidably secured to the edge of a slideable door and with the upper end thereof projecting upwardly, an angular-shaped lever pivotally secured through the vertex thereof to the mounting angle with one end of the lever being pivotally secured to one end of the arm member and with the opposite end thereof being pivotally secured to the upper end of a second door operating arm, said second door operating arm having a break joint formed in the length thereof with the lower end of said second door operating arm being slidably secured to the edge of a slideable door, a horizontally positioned arm member pivotally secured through the upper end of the first mentioned door operating arm and supported at the opposite end thereof by means of another bar member, and means rigidly secured to and carried by the horizontally positioned bar member for simultaneously operating a second set of slideable doors.

JAMES E. BANCROFT.
